UNITED STATES PATENT OFFICE.

BERNARD SUMMERFIELD, OF CHICAGO, ILLINOIS.

SHOE HEEL.

1,426,019.

Specification of Letters Patent. Patented Aug. 15, 1922.

Application filed October 23, 1920. Serial No. 413,974.

To all whom it may concern:

Be it known that BERNARD SUMMERFIELD, a citizen of the United States of America, residing at the city of Chicago, in the county 5 of Cook and State of Illinois, has invented certain new and useful Improvements in Shoe Heels; and he does hereby declare the following to be a full, clear, and exact description of the invention, such as will enable others skilled in the art to which it 10 pertains to make and use same.

This invention relates to new and useful improvements in shoe heels and more particularly to what is known in the art as a 15 detachable heel. The main object of this invention is the provision of a shoe heel and means whereby the heel can be quickly and readily attached to the body of the shoe or removed therefrom when so desired.

20 Another object of the present invention is the provision of means including a plate attached to the body of a shoe for detachably securing the heel to the shoe, the heel being provided with means for engaging portions 25 of the plate to retain the same in its proper position with respect to the body of the shoe and while securely held in position can be quickly and readily detached from the shoe 30 at any time.

35 A further object of the invention is the provision of a detachable shoe heel, whereby either a wooden heel or a heel of any other material can be quickly and readily attached to the body of a shoe and securely held in its proper position or can be readily detached 40 when so desired.

With the above and other objects in view, the invention consists in the novel features of construction, the combination and arrangement of parts hereinafter more fully 45 set forth, pointed out in the claim and shown in the accompanying drawings, in which

Figure 1 is a side elevation of a shoe heel, 50 parts thereof being broken away and illustrated in section to show the application of my improved detachable heel,

Figure 2 is a perspective view of the heel,

Figure 3 is a perspective view of the attaching plate,

Figure 4 is a transverse sectional view, illustrating a slightly modified form of plate.

55 In carrying out my invention, I first provide the heel member 1 with a longitudinal slot 2, having undercut grooves 3 in the side

walls thereof, to provide a substantially T-shaped slot formed in the upper face of the heel 1. Arranged within this slot is a correspondingly shaped metal plate 3', having a 60 tongue *a* struck up from the central portion thereof, as illustrated in Figure 2, said tongue being movable within the slot 2 and adapted to be pressed downwardly into the bottom of the slot so that the upper face 65 thereof will lie flush with the body portion of the plate 3'.

The body of the shoe, most generally indicated by the numeral 4, has attached to its heel portion a metal plate 5, said plate being 70 securely fastened to the body of the shoe by means of screws or other fastening members adapted to be extended through the openings 6 in the plate and engaged with the shoe 4. The plate 5 is provided upon one 75 face thereof with the spaced outstanding ears 7, having flanges disposed at right angles to the ears, the outer ends of which project beyond the side portions of the ears, as indicated at 8 to form engaging flanges. 80

From this, it will be noted that when the heel member 1 is attached to the body of the shoe, the flange portions 8 will engage within the undercut grooves of the plate 3' while the ears 7 will be disposed within the longitudinal groove 2. In order to retain the heel member 1 in a locked position with respect to the shoe 4 after the same has been attached thereto, the tongue *a* will spring outwardly and engage with the ear 7 at the rear 90 of the heel, as clearly indicated in Figure 1, thus preventing the removal of the heel 1 from the plate 5.

In order to attach the heel member 1 to the body of the shoe 4, the tongue *a* is depressed so that it will pass beneath the first one of the flanges 8 when the same are inserted within the undercut grooves in the plate 3' and after passing beneath this flange, the tongue will spring outwardly to 100 the position illustrated in Figure 1. After the heel has been moved to its proper position with respect to the shoe, the same is secured in position by having the screw members 10 extending through the openings 11 105 in the down-turned ear 9 of the plate 5 and engaging with the heel member 1, as illustrated in Figure 1. The plate 3' is also provided with a perforated ear *b* and the screw 110 passes through this plate prior to entering the body of the heel 1.

In order to remove the heel member 1

from the body of the shoe, an instrument is inserted through the openings *c* which are formed within the ear 9 and the forward one of the ears 7 until the same engages the tongue *a* whereby it can be depressed downwardly and disengaged from the rearmost ear 7 so that this ear will readily pass over the tongue and permit the removal of the heel 1.

10 In Figure 4, I have illustrated a slightly modified form of the invention wherein one of the flange members is formed integral with the stop plate 9 instead of providing an ear 7 on the plate 5. This flange member, 15 which is indicated by 8', is arranged upon the stop plate 9 in such a position that it will be readily received into the undercut grooves 3 of the heel 1.

What I claim is:

20 The combination with a shoe having a plate attached to the heel portion thereof,

spaced outstanding ears formed on said plate, flanges disposed at right angles to the ears and having their ends projecting beyond the side portions of the ears and a 25 down turned ear formed at one end of the plate, of a heel member having a longitudinal slot provided in its side walls with undercut grooves to receive the projecting ends of the flanges, a correspondingly shaped 30 metal plate arranged within said slot and grooves, a tongue struck up from the central portion of said plate and normally projecting upwardly within the slot for engagement with one of the outstanding ears on 35 the plate when the heel is attached to the shoe and means for connecting the down turned ear on the plate to the body of the heel as and for the purpose set forth.

In testimony whereof I affix my signature. 40

BERNARD SUMMERFIELD.
